UNITED STATES PATENT OFFICE.

DAVID N. LONG, OF BUFFALO, NEW YORK, ASSIGNOR TO J. B. COLT COMPANY, OF NEW YORK, N. Y., A CORPORATION OF NEW YORK.

ACETYLENE-GAS GENERATOR.

SPECIFICATION forming part of Letters Patent No. 687,534, dated November 26, 1901.

Original application filed January 16, 1896, Serial No. 575,711. Divided and this application filed August 17, 1901. Serial No. 72,331. (No model.)

To all whom it may concern:

Be it known that I, DAVID N. LONG, of Buffalo, in the State of New York, have invented certain new and useful Improvements in Generators for Acetylene and other Gases, of which the following is a specification, illustrated by accompanying drawings, being a division of my application, Serial No. 575,711, filed January 16, 1896.

10 The invention is designed with particular reference to the production and control of gases generated by bringing in contact water and one of the metallic carbids, calcium carbid being at present most used. Generators 15 of this type may be divided into two classes: first, those in which the water is carried above the carbid-chamber, and, second, those in which the carbid-chamber, whether for pulverized or lump carbid, is carried over the 20 water-chamber. The present invention belongs to the latter class and is a division of my application filed January 16, 1896.

In generators where the carbid-chamber is above the water-chamber I have found it 25 highly desirable to have an automatically-controlled valved passage-way directed downward for affording a controllable communication between the water and the carbid and for allowing the fine granular material, 30 whether carbid or its residuum—calcium hydrate—to fall down into the lower chamber. This chamber must be cleaned out from time to time. The construction of the passage-way and the stop or valve should be such that 35 when no gas is being used the valve will tend to exclude moisture and vapor from the water as well as merely keeping the carbid and the water apart. Where pulverized carbid is to be used and dropped through the valve 40 little by little into the water as required, it is only necessary to incline the portions of the carbid-chamber in the vicinity of the passage-way sufficiently to permit the slipping of the material along such incline; but where, on 45 the other hand, it is intended that the water shall rise through the valved passage-way and reach the carbid as required from time to time there the residuum in the wet state must slide along the incline and reach the

valved passage-way and drop through it without blocking or interfering with the valve or stop.

The object of the present invention is to produce an apparatus fulfilling all these requirements and reliable, safe, and efficient 55 in operation.

The accompanying drawings illustrate the invention as proportioned and arranged for raising the water up to the carbid, these being the more severe conditions, and from 60 these the use of the invention under the other and more simple conditions will be readily understood by those skilled in the art.

Figure 1 is a vertical central section of a generator embodying the invention in one 65 form. Fig. 2 is a detached vertical central section, on an enlarged scale, showing the valve and its seat.

Within the outer casing *b* for the water is placed a gas holder or bell *c*, containing the 70 carbid-chamber *d*. It must not be understood that the invention is restricted to such a form of expandible gas-holder, as other forms are well known. The bottom *f* of the carbid-chamber converges downward and is 75 provided with an opening or passage-way *g*, delivering into the water-chamber *b* beneath. I have selected for illustration a form of my invention that is best adapted when the gas-holding bell is sufficiently heavy or weighted 80 to cause the water to rise through the opening *g* instead of allowing powdered carbid to fall through the opening *g*. Consequently this form of my apparatus may, if desired, utilize lump-carbid and depend on the water rising 85 to the carbid instead of necessitating the employment of pulverized carbid; but in the latter case the gas-bell *c* need not be so heavily weighted or a lower water-level may be used, as the water should never be allowed to rise 90 to the opening *g*. The opening *g* is provided with a valve or stop *h*, which is preferably connected with or supported from the bottom of the outer casing *b*, so that there will be a relative movement between the valve and its 95 seat or passage-way *g* when the bell *c* rises or falls. The valve and its seat are not fitted one to another so as to seat the valve upon a

considerable area of surface or seat, as is customary in valves for liquids; but as the valve has to operate and seat itself notwithstanding the presence of granular or gritty material the valve and its seat come together only along a fine annular line or edge of contact, as shown on an enlarged scale in Fig. 2. In order to prevent too great an accumulation of carbid residue (or of carbid, as the case 10 may be) in the vicinity of the valve or stop *h* and its seat, I provide a carbid-support *j*, so placed that it protects the valve *h* and its opening or seat *g* from the direct pressure of the entire mass of carbid. The falling carbid or carbid residuum, as the case may be, must pass through the indirect or tortuous annular space between the support *j* and the inclined bottom *f* to reach the valve *h*, and consequently only a very thin and light layer 20 of material can slip down to the valve and the opening *g* at any time. This insures free action between the opening *g* and its valve or stop. In the form of the invention shown the carbid-support *j* may preferably be carried by the rod *k* and pins *l* on the bottom of the apparatus, as this takes the varying weight of the carbid off the bell and is not objectionable, except where very large charges of powdered carbid are to be used. When 30 the apparatus is designed to operate by the rise of water to the carbid, the support *j* should be a sieve or be perforated, so as to allow the water to easily reach the bottom of the carbid.

Instead of allowing the carbid or its residue 35 to fall directly to the bottom of the water-chamber I may employ a receptacle *m*, having two openings and valves or covers *o* and *p* therefor, which can be operated from outside the apparatus and have a chute *q*, which 40 directs the residue as it settles through the water into the receptacle *m*. The valve *o* is kept open for this purpose and the valve or cover *p* closed during the normal operation of the apparatus; but by closing the valve *o* and opening cover *p* the residue may be removed from the receptacle *m* without interfering with the rest of the apparatus, and then the cover *p* may be closed and the valve *o* again opened.

50 Around the gas-holder I may provide an annular flotation air-chamber *r*, open at the bottom only. For the purpose of readily modifying and regulating the weight, or rather the downward pressure, of the gas-bell I provide a screw-threaded rod *t*, secured centrally on a cross-piece *u* across the lower portion of the gas-bell *c*, and upon this I screw an adjustable follower *t'* and an upward-pressing spring *t''*. By adjusting the 55 follower *t'* on the rod *t* a greater or less upward pressure is exerted upon the gas-bell, and thereby tends to decrease the effective 60 gas-pressure under which the apparatus operates.

65 At *v* and *v'* are shown certain water-holding chambers that form the subject of a divisional application and are of no interest in

this present case, except so far as they may be made use of for regulating the weight of the floating gas-bell.

70 At *w* are shown catches which engage the projections *w'* when the gas-bell is raised sufficiently by hand. When so engaged and held, the operation of the apparatus will be suspended, the valve *h* closed, and the top or cover *d'* of the carbid-chamber may be taken off, giving access to the interior for cleaning and charging it.

The gas may be led from the gas-holder through any suitable connection and valve *x* 80 directly or indirectly to any suitable burners.

The operation of the apparatus shown is as follows: The gas-bell is raised and held up by the catches *w w'* while the carbid is being put in. The requisite amount of water should 85 be in the water-chamber, enough being used to insure its rising within the bell and reaching the carbid when the bell sinks to the position shown if lump-carbid is employed. After the top *d'* has been screwed on tightly 90 the bell may be lowered slowly after releasing the catches *w* until the valve *h* is raised relatively to its seat, (which occurs by the lowering of the seat.) Thereupon communication between the carbid and the water is 95 opened and the generation of gas begins. The gas generated immediately causes the bell to rise, closing or nearly closing the valve or stop *h*, and thereby shutting off the communication between water and carbid until 100 the gas is drawn off and a new supply required. In practice when the apparatus is running the total vertical movement of the bell and consequent opening and closing of the valve or stop *h* is very slight. When 105 lump-carbid is used, the water rises above and falls beneath the valve, and when powdered carbid is used the carbid falls through the valve into the water beneath and generates gas until the valve is so nearly closed as 110 to prevent any more carbid falling. As the gas is drawn off the valve of course opens slightly. The water-level will be kept down at a lower level when operating with powdered carbid and a slightly greater pressure consequently produced if other conditions, such 115 as the weight of the moving parts, are the same. As the material falls through the opening *g* the residue passes into the chamber *m*, as already explained.

120 I desire to point out a radical difference between my invention and such devices as are shown in the Dickerson patent, No. 541,526. In that patent device only a determined quantity of carbid can be fed to water or determined quantity of water be fed to carbid at intervals, and the feeding device, if it can be called a "valve" in any sense, is not a valve in the sense of my patent, because it can never leave a restricted, but open, passage-way between the carbid and the water. In my invention, on the other hand, a stop or valve may close the opening or passage-way entirely or may control and restrict the con-

tinuous flow of materials through a slightly opened passage-way.

In order to point out the features of my invention that I claim broadly as new and characteristic, however they may be utilized in generators of this class, I make the following claims:

1. In a generator of the type wherein a solid material such as carbid or its residuum passes downward through an opening or passage-way into a chamber beneath, the combination of a liquid-holding tank and a solid-holding receptacle or chamber provided with an opening or passage-way leading downward from the said solid-holding receptacle and provided with a seat for a valve or stop, and a valve or stop therefor adapted to feed solid or granular materials and coöperating with said seat to open and close without clogging with the said solid or granular materials, the valve when seating making contact with its seat along a substantially narrow line in contradistinction to seating upon a broad and fitted surface, and means controlled by the gas generated for giving relative adjustment between the valve or stop and its seat, substantially as set forth.

2. In a generator of the type wherein a solid material such as carbid or its residuum passes downward through an opening or passage-way into a chamber beneath, the combination of a liquid-holding tank and a solid-holding receptacle or chamber provided with an opening or passage-way leading downward from the said solid-holding receptacle, a valve or stop therefor, which meets the said opening at a substantially narrow annular line of contact in contradistinction to being seated upon a broad and fitted surface when closed, and leaves a substantially free passage through which granular or fine solid material may pass when open, and means controlled by the gas generated for giving relative adjustment between the valve or stop and the opening, substantially as set forth.

3. In a generator of the type wherein a solid material such as carbid or its residuum passes downward through an opening or passage-way into a chamber beneath, the combination of a liquid-holding tank and a solid-holding receptacle or chamber provided with a bell which rises and falls in the said tank and with an opening or passage-way leading downward from the said solid-holding receptacle and provided with a seat for a valve or stop, and a valve or stop therefor adapted to feed solid or granular materials and coöperating with said seat to open and close without clogging with the said solid or granular materials, the valve when seating making contact with its seat along a substantially narrow line in contradistinction to seating upon a broad and fitted surface, and means controlled by the gas generated for giving relative adjustment between the valve or stop and its seat, substantially as set forth.

4. In an acetylene-generator, the combina-

tion of chambers for the carbid and for the water, an opening or passage-way affording communication between said chambers, toward which the bottom of the carbid-chamber is convergent and inclined or funnel-shaped, a valve for controlling the freedom of communication through said opening or passage-way, the valve when seating making contact with its seat along a substantially narrow line in contradistinction to seating upon a broad and fitted surface, substantially as set forth.

5. In an acetylene-generator, the combination of chambers for the carbid and for the water, an opening or passage-way affording communication between said chambers, and a carbid-support within the carbid-chamber supported through the opening or passage-way independently of the walls of the said carbid-chamber, substantially as set forth.

6. In an acetylene-generator, an upper chamber for carbid, a lower chamber for water beneath, an opening or passage-way from one to the other, a stop or valve for the said opening, the valve when closed making contact with said opening or passage-way along a substantially narrow line in contradistinction to seating upon a broad and fitted surface, and gas-actuated means for controlling the freedom of passage between the said stop or valve and the walls of said opening or passage-way.

7. In an acetylene-generator, a carbid-chamber, a water-chamber beneath, an opening or passage-way from one to the other, a support for carbid and a stop or valve for the said opening or passage-way, both within the carbid-chamber, and an instrumentality outside of said chamber connected to carry the said stop or valve, substantially as set forth.

8. In combination in an acetylene-generator, a carbid-chamber having a discharge opening or passage-way directed downward and means for supporting the carbid at least partially and preventing it from falling vertically into said opening or passage-way, and means for controlling the freedom of passage through said opening or passage-way.

9. In combination in an acetylene-generator, a carbid-chamber having a discharge opening or passage-way directed downward, a stop or valve therefor, means for effecting a relative movement between the passage-way and the stop or valve, and means within the chamber for taking the weight of the carbid at least in part from the vicinity of said stop or valve and its seat for the purpose of facilitating such relative movement.

10. In combination in an acetylene-generator, a carbid-chamber having a discharge opening or passage-way directed downward, and a converging bottom leading to said opening or passage-way, a stop or valve for controlling the freedom of passage through the opening or passage-way, and means for taking the weight of the carbid from the said bottom in the vicinity of the said stop or

valve, for the purpose of facilitating the relative movement between said stop or valve and the surface upon which it is seated.

11. In combination in an acetylene-generator, a carbid-chamber having a discharge opening or passage-way directed downward through its bottom, and means above said opening or passage-way for supporting material at least partially, but leaving an annular space around such means, whereby only the particles falling through the annular space may press toward said opening or passage-way.

12. In an acetylene-generator having a carbid-chamber with a water-space beneath it, a tortuous means of communication from the carbid to the water-space, whereby the whole weight of the carbid or the residuum of carbid may not press freely toward said communication, and means for controlling the freedom of passage through such means of communication, leaving a through-passage for the materials when opened, substantially as set forth.

13. In an acetylene-generating apparatus having a carbid compartment or chamber located above a water-space and having also an expansible gas-holder, the combination in such apparatus of a stop or valve that leaves a through-passage for materials when opened for controlling the freedom of communication between the carbid and the water, and connections for relatively adjusting said stop or valve and the coöperating surface or seat by the expansion and closing of the said expansible gas-holder, the valve when seating making contact with its seat along a substantially narrow line in contradistinction to seating upon a broad and fitted surface, substantially as set forth.

14. In an acetylene-generating apparatus having a carbid compartment or chamber located above a water-space and having also an expansible gas-holder, the combination of a spring for the said expansible holder, and means for adjusting the tension of such spring, substantially as set forth.

15. In an acetylene-generating apparatus having a carbid compartment or chamber located above a water-space and having an expansible gas-holder, the combination of a spring acting on the expansible holder and tending to vary its expansion, and means for

controlling the communication between carbid and water actuated by the movement of 55 the said holder.

16. In an acetylene-generator the combination with an outer vessel for holding water of a buoyant vessel open at the bottom and provided with a carbid-chamber having a converging bottom, of a stationary plug-valve arranged centrally of an opening at the bottom of the said receptacle, the valve when seating making contact with its seat along a substantially narrow line in contradistinction to seating upon a broad and fitted surface, and means for closing the valve automatically when the buoyant vessel is raised by the gas generated within it.

17. In an acetylene-gas generator of the type 70 in which the carbid-chamber is above the water-chamber and in which carbid or carbid residuum falls through an opening into the water-chamber, the combination of a downward-converging bottom having a seat for a stop or 75 valve, and a stop or valve therefor concentric with the said seat which leaves a substantially free passage for the granular or solid materials, the valve when seating making contact with its seat along a substantially narrow line in contradistinction to seating upon a broad and fitted surface, and means for giving a movement of separation or approach between the seat and the stop or valve, and for regulating the annular interval between 80 them, substantially as set forth.

18. In an acetylene-generator of a type wherein the carbid-chamber is above the water-chamber, the combination of the water-holding chamber, a valve or stop for controlling the feeding of the carbid or its residuum 90 into the said water-holding chamber, a receptacle or chamber for receiving the carbid waste or residuum, a passage-way from the water-holding chamber to the said receptacle 95 or chamber, a valve for said passage-way, and a second passage-way leading out of the said receptacle and provided with means for closing such passage-way, substantially as set forth.

Signed this 5th day of August, 1901, at Buffalo, New York.

DAVID N. LONG.
